(57) **CLAIM**

The ornamental design for an ashtray, as shown and described.

DESCRIPTION

FIG. 1 is a perspective view of an ashtray showing my new design;

FIG. 2 is an alternative perspective view thereof;

FIG. 3 is a front view thereof;

FIG. 4 is a back view thereof;

FIG. 5 is a left side view thereof;

FIG. 6 is a right side view thereof;

FIG. 7 is a top plan view thereof;

FIG. 8 is a bottom plan view thereof; and,

FIG. 9 is an enlarged view of the portion labeled "9" shown in FIG. 1.

The broken lines are for purposes of annotating the enlarged view only and forms no part of the claimed design.
